UNITED STATES PATENT OFFICE

145,917

DESIGN FOR A COMBINED PLANT CONTAINER AND SUPPORT

Adina Ames, Milwaukee, Wis.

Application June 1, 1945, Serial No. 119,850

Term of patent 14 years

(Cl. D35—3)

To all whom it may concern:

Be it known that I, Adina Ames, a citizen of the United States of America, residing at Milwaukee, county of Milwaukee and State of Wisconsin, have invented a new, original, and ornamental Design for a Combined Plant Container and Support, of which the following is a specification, reference being had to the accompanying drawing, forming a part thereof wheren:

I claim:

The ornamental design for a combined plant container and support, as shown.

ADINA AMES.
